(57) **CLAIM**

We claim the ornamental design for a bag support, as shown and described.

DESCRIPTION

FIG. 1 is a front perspective view of a bag support;
FIG. 2 is a rear perspective view of a bag support of FIG. 1;
FIG. 3 is a front view of a bag support of FIG. 1;
FIG. 4 is a rear view of a bag support of FIG. 1;
FIG. 5 is a right side view of a bag support of FIG. 1, the left side is a mirror image of the right side view of FIG. 5;
FIG. 6 is a top view of a bag support of FIG. 1; and,
FIG. 7 is a bottom view of a bag support of FIG. 1.
